UNITED STATES PATENT OFFICE.

GEORGE F. FISHER, OF NORTH TONAWANDA, NEW YORK.

BUILDING CONSTRUCTION.

SPECIFICATION forming part of Letters Patent No. 791,980, dated June 6, 1905.

Application filed July 16, 1904. Serial No. 216,813.

To all whom it may concern:

Be it known that I, GEORGE F. FISHER, a citizen of the United States, residing at North Tonawanda, in the county of Niagara and State 5 of New York, have invented certain new and useful Improvements in Building Constructions, of which the following is a specification.

This invention relates to improvements in 10 building constructions; and it has for its object the production of composition building-blocks used as a veneering to cover a frame in a perfectly reliable manner by the use of unskilled labor and to provide blocks for use 15 in such construction whereby a perfect alinement of the same may be obtained.

To these ends the invention consists in the construction, arrangement, and combination of parts to be hereinafter described, and par- 20 ticularly pointed out in the appended claims.

In the drawings, Figure 1 is a vertical section of a wall constructed according to my in- 25 vention. Fig. 2 is a longitudinal vertical section taken on line $y-y$, Fig. 1. Fig. 3 is a detached perspective view of a block embodying my invention. Fig. 4 is a vertical section of a wall, showing the lower projecting securing end of each block provided with teeth adapted to be embedded in the retainer-bars 30 of the frame. Fig. 5 is a longitudinal vertical section taken on line $z-z$, Fig. 4. Fig. 6 is a detached perspective view of one of the blocks used in the form of my invention illus- 35 trated in Figs. 4 and 5.

Referring to the drawings in detail, simi- 35 lar numerals of reference refer to similar parts in the several figures.

The numeral 1 designates the foundation, which may be of any construction.

40 2 designates the frame, and 3 the building-blocks, which are supported on the frame, the latter serving as a foundation for the blocks.

The frame in its preferred form consists of 45 uprights or studs 4, separated by suitable spaces, and ledges or projecting horizontal members, preferably in the form of retainer bars or strips 5, secured to the uprights and spaced to correspond with the height of the blocks, each retainer-bar being positioned di-

rectly in rear of the upper marginal portion 50 of a horizontal row of blocks.

The blocks are formed of any suitable composition and are preferably of rectangular formation. Embedded in each block are securing-irons 6 in the form of flat bands bent 55 to form an embedded portion 7, which ex- tends from edge to edge of the block, and free securing end portions 8, arranged at right angles to said embedded portion and extend- 60 ing beyond the rear face of the block, each 65 free end portion having a nail-aperture 9, through which nails 10 pass and enter the horizontal retainer-bars. The upper free end of each iron bears directly against its coöper- 70 ating retainer-bar, and the lower end there- 75 of lies in a plane above its coöperating re- tainer-bar, the nail passing through the lat- ter end simply serving to prevent outward or inward movement of the block. This con- struction permits of a perfect alinement of 70 the blocks, which assures an even and true surface, such alinement being obtained by reason of the securing ends of the irons be- 75 ing of a length to permit the blocks to be moved outward or inward, as may be neces- sary, the securing-nails 10 being driven into the retainer-bars at any point in the width thereof.

As the frame is preferably constructed of 80 undressed lumber, which is generally of un- equal thickness or width and often curved in length, the row of base-blocks which are laid directly on the foundation are separated from the coöperating retainer-bar by a space 11 85 of sufficient size to permit of perfectly alin- 85 ing the blocks, even though the remaining retainer-bars be of increased thickness.

In Figs. 4 to 6 the construction of the blocks and the application thereof to the frame are 90 similar to the blocks just described, with the exception that the lower projecting securing end of each securing-iron is provided with a 95 depending toothed extension 12, adapted to be driven partly into the retainer-bars instead of securing the lower ends of said irons with nails.

Having thus described the invention, what I claim is—

1. A building-block having a securing-iron embedded therein, said securing-iron having an embedded portion extending through the block and two end-securing portions arranged at right angles to the embedded portion, said end-securing portions extending inward beyond the inner face of the block and having their outer faces flush with opposite edges of the block.
2. A structure comprising uprights, building-blocks set edge upon edge, and retainer-bars secured to the uprights and spaced to sit in rear of corresponding marginal portions of the blocks, each block having a securing-iron embedded therein, and each securing-iron having its ends bent at right angles to project beyond the inner face of the block at opposite edges thereof, the lower projecting ends of the irons in one row of blocks and the upper projecting ends of the irons in the adjacent row of blocks being secured to one retainer-bar.
3. A structure comprising a frame having horizontal retainer-bars, and building-blocks set edge upon edge, each block having a securing-iron embedded therein, and each securing-iron having an embedded portion extending through the block and two end-securing portions arranged at right angles to the embedded portion, said end-securing portions extending inward beyond the inner face of the block and being secured to said retainer-bars.
4. A structure comprising a frame having retainer-bars, and building-blocks set edge upon edge and having securing-irons embedded therein, each securing-iron having its ends bent at right angles to project beyond the inner face of the block at opposite edges thereof, one projecting end of each securing-iron having a toothed depending extension adapted to be partly embedded in the retainer-bars.
5. A structure comprising a frame having horizontal retainer-bars, and building-blocks set edge upon edge, each block having at least one securing-iron embedded therein and each securing-iron having a projecting end provided with depending teeth adapted to be driven into the retainer-bars.

In testimony whereof I have affixed my signature in the presence of two subscribing witnesses.

GEORGE F. FISHER.
